UNITED STATES PATENT OFFICE.

ARTHUR C. ALtenburg, OF MILWAUKEE, WISCONSIN.

SHIRT SLEEVE WITH DETACHABLE CUFF.

Application filed October 27, 1921. Serial No. 510,731.

To all whom it may concern:

Be it known that I, ARTHUR C. ALtenburg, a citizen of the United States, residing at Milwaukee, in the county of Milwaukee and State of Wisconsin, have invented certain new and useful Improvements in Shirt Sleeves with Detachable Cuffs, of which the following is a specification.

This invention relates to shirt attachments and the primary object of the invention is to provide a novel cuff for a shirt sleeve which can be readily detached when worn or soiled to permit a fresh clean cuff to be substituted therefor so that the shirt can be worn a relatively long time without laundering, and whereby the necessity of discarding a shirt when the cuffs thereof become frayed is obviated.

In the so called soft shirts and cuffs, the cuffs become soiled before the body portion of the shirt, and as the cuffs are permanently secured to the shirts, the whole shirt has to be laundered when in reality the cuffs are the only parts that are soiled. Further, in soft cuffs they become quickly frayed and worn, due to the fact that they are folded intermediate their edges which weakens the same. This renders it necessary to discard the whole shirt when only the cuff parts are worn.

It is therefore another prime object of this invention to provide either a soft or stiff cuff embodying a single straight body, having means disposed intermediate its longitudinal edges for permitting the ready attachment thereof to a shirt sleeve, said means permitting the cuff to be swung around in order to reverse the position of the upper and lower edges thereof, so that when the lower edge becomes soiled, the upper clean edge can be brought into active position in lieu of the soiled edge.

With these and other objects in view, the invention consists in the novel construction, arrangement and formation of parts, as will be hereinafter more specifically described, claimed and illustrated in the accompanying drawings, forming a part of this application, in which drawings:

Figure 1 is an inner elevation of a cuff constructed in accordance with this invention.

Figure 2 is an elevation of a shirt sleeve spread out and showing the novel means associated therewith for permitting the novel

cuff to be readily and quickly connected therewith.

Figure 3 is a perspective view showing a cuff constructed in accordance with this invention being attached to a shirt sleeve. 60

Figure 4 is an inner perspective view of a cuff attached to a shirt sleeve, the shirt sleeve and cuff being constructed in accordance with this invention.

Figure 5 is an enlarged sectional transverse view through a cuff showing the same attached to a shirt sleeve. 65

Figure 6 is an inner elevation of a modified form of cuff, illustrating the different means carried thereby for permitting the same to be attached to a shirt sleeve. 70

Referring to the drawings in detail, wherein similar reference characters designate corresponding parts throughout the several views, the letter A indicates a cuff 75 constructed in accordance with the invention; and B, a shirt sleeve.

The cuff A includes a longitudinally extending body 10, which can be laundered either soft or stiff, and this cuff is so constructed and associated with the shirt sleeve B in such a manner as to render it unnecessary to fold the cuff intermediate its edges as now contemplated in cuffs of the soft variety already upon the market. It is preferred 80 that the cuff include inner and outer plies 11 and 12 of the material from which the shirt is formed and suitably stiffened by an inner ply of stiffener material 13. The inner face of the body portion 10 of the cuff A supports 85 or has secured thereto in any preferred manner the attaching band 14. This band 14 extends longitudinally of the cuff and is preferably positioned at the longitudinal center thereof so that the same will be positioned directly intermediate the longitudinal edges of the cuff. The terminals of this attaching band 14 terminate short of the button holes 15 of the cuff which are adapted 90 to receive any preferred type of cuff button. As shown in Figure 1 of the drawings, the attaching band 14 supports a plurality of buttons 16. The buttons 16 are located adjacent to the ends of the bands and at an intermediate point of the band. 95

The shirt sleeve B is also of novel construction and the terminal of the sleeve proper is provided with a band 18 to which the cuff A is adapted to be removably secured. This band 18 is folded to provide a 100 105 110

flap 19, which may be sewed at its transverse edges as at 20 and its outer longitudinal edge as at 21 to the main body portion of the band leaving a flap which has its upper 5 end free or unattached. This flap is provided adjacent to its terminals with button holes 22 and at an intermediate point with a button hole 23 and these button holes 22 and 23 are adapted to receive the buttons 10 16 carried by the attaching band 14 of the cuff.

Now, it can be seen that when the cuff is secured to the shirt sleeve, a portion thereof will extend above and below the terminal 15 portion of the sleeve, thereby giving the appearance of a folded cuff which is so desirable by discriminating persons. One edge of the sleeve B at one terminal of the band 18 can be provided with a tab 24, which 20 may be provided with a buttonhole 25 for the reception of a button 26 carried by the other edge of the sleeve. This tab 24 provides means for holding the edges of the sleeves in special relation so as to render 25 the sleeve cool in summer. While the tab 24 holds the edges of the sleeves in spaced relation, it at the same time holds the sleeve in corrected position.

In order to prevent the spreading of the 30 flap 19 from the body portion 17 of the sleeve B, the same is sewed or otherwise secured to the body portion 17 of the sleeve intermediate the button holes 22 and 23 as at 29.

35 While of course, any preferred type of cuff button can be used with the cuff, a button 30 has been shown which is of the two-part clasp type.

It is obvious that various ways of attaching 40 or connecting the attaching band 14 to the shirt sleeve B can be had, such as the substitution of snap fasteners for the buttons 16, and the button holes 22 and 23.

In Figure 6 is illustrated a modified means 45 of connecting the cuff A to the sleeve B and in this instance an attaching band 35 is secured to the body portion 10 of the cuff.

This attaching band 35 is provided adjacent to its terminals with button holes 36 50 and intermediate its ends with a button hole 37. These buttonholes are adapted to receive buttons which can be carried by the end or wrist band of the said sleeve. The attaching band 35 is secured at its ends by a line of transverse stitching 38 to the body portion 10 of the cuff and intermediate its ends between the button holes 36 and 37 by a row of stitching 39. The rows of stitching 39 prevent the sagging of the attaching band 60 or strip 35 away from the body of the cuff.

The modification shown in Figure 6 is similar to the cuff shown in Figure 1, the only difference being that the buttons in one instance are attached to the cuff and the buttonholes formed in the shirt sleeve, while in

the other instance the buttons are carried by the shirt sleeve and the button holes formed in the cuff.

In the use of the improved cuff, the same is connected to the sleeve in the manner heretofore described, and when the cuff becomes worn or soiled, it is merely necessary to detach the same from the sleeve and substitute a new cuff therefor. If simply the outer edge of the cuff becomes soiled, it is merely necessary to unfasten the ends of attaching band 14 or 35 from the shirt sleeve and turn the cuff on the central button as a pivot, so as to bring the inner edge to an outermost position, thus presenting a clean edge of the cuff to the front. The end portions of the cuff are then secured to the shirt sleeve.

From the foregoing description, it can be seen that a novel sleeve and cuff has been provided for shirts, in which a clean fresh cuff can be attached to the sleeve at any time and discarded when worn or frayed.

Changes in details may be made without departing from the spirit or scope of this 90 invention; but,

I claim:

1. A detachable cuff comprising an elongated cuff body having cuff button receiving openings formed adjacent the terminals thereof at the longitudinal center of the body, and a plurality of connecting members carried by said body at the longitudinal center thereof, certain of said connecting members adjacent to said button holes. 100

2. A detachable soft cuff comprising an elongated body portion, an elongated attaching strip secured to the body portion longitudinally thereon intermediate its longitudinal edges, and a plurality of fastening devices spaced longitudinally of and carried by the attaching strip for permitting the removable attachment thereof with a shirt sleeve at a plurality of points. 105

3. A detachable soft cuff comprising a single flat body portion, a longitudinally extending attaching strip secured to the inner face of the body portion intermediate its longitudinal edges and at the longitudinal center thereof, a plurality of connecting elements carried by the band at spaced points throughout its entire length, the terminals of the cuff being provided with cuff button receiving openings. 110

4. As a new article of manufacture, a detachable cuff for shirt sleeves comprising a single flat body portion having cuff button receiving openings formed adjacent to the terminals thereof at the longitudinal center of the body, a longitudinally extending attaching strip secured to the inner face of the body portion intermediate the longitudinal edges thereof and at the longitudinal center thereof, the terminals of the attaching strip terminating short of the 120 125 130

cuff button receiving openings, and a plurality of connecting members carried by the attaching strip at predetermined spaced points throughout the length thereof.

5. The combination with a shirt sleeve having a wrist band, and means for securing the terminals of the wrist band together, of a removable cuff therefor including a single flat body, a longitudinally extending attaching strip secured to the inner face of the cuff body at the longitudinal center thereof, and interconnecting means carried by the wrist band and attaching band.

6. The combination with a shirt sleeve having a wrist band, means connecting the

terminals of the wrist band together, a flap secured to the wrist band having a plurality of buttonholes therein, of a removable cuff therefor including a flat body portion having terminal buttonholes therein for the 20 reception of a cuff button, a longitudinally extending attaching strip secured to the inner face of the body portion of the cuff at the longitudinal center thereof, the terminals of the attaching strip terminating short of 25 the cuff button holes, and buttons carried by said attaching band for engaging in the button holes formed in the flap carried by the wrist band.

ARTHUR C. ALTBURG.
